UNITED STATES PATENT OFFICE

CLINTON H. M. BULL, OF HOUSTON, TEXAS

DRILL

Application filed December 11, 1928. Serial No. 325,299.

This invention relates to new and useful improvements in a drill.

One object of the invention is to provide a novel type of drill of the rotary type and comprising a head and a detachable blade secured therein and which may be readily removed therefrom when desired.

Another object of the invention is to provide a rotary drill which includes a drill head, a blade therein having cutting edges, said head being formed to reinforce or brace the blade behind the cutting edges thereof, said blade being detachable and novel means in the head for securely locking or anchoring the blade in the head, when the drill is in use, and for releasing said blade to permit its removal, when desired, as when it becomes necessary to replace a worn blade with a new one.

A further feature of the invention is to provide a drill of the character described which is composed of a few parts, which is very strong and durable and which is very economical in use due to the fact that when the drill becomes dull, or the blades become broken or worn, new blades can be substituted, from time to time, for the old ones and the head re-used.

With the above and other objects the invention has particular relation to certain novel features of construction, arrangement of parts and use, an example of which is given in this specification and illustrated in the accompanying drawings wherein:—

Figure 1 shows a side view of the complete drill.

Figure 2 shows a side view of the blade.

Figure 3 shows a bottom end view of the drill.

Figure 4 shows a side view of the drill head partly in section.

Figure 5 shows an elevational view of the drill and taken at right angles to the view shown in Figure 4.

Figure 6 shows a side view of the key block employed.

Figure 7 shows a side elevation of the filler block employed.

Figure 8 shows an elevational view of the drill, partly in section, and taken at right

angles to the view shown in Figure 4, and Figure 9 shows a bottom plan view of the key block.

Referring now more particularly to the drawings wherein like numerals of reference 55 designate similar parts in each of the figures the numeral 1 designates the drill head, as a whole, whose upper end is, preferably, reduced forming a shank 2 whose upper end is threaded as at 3 for the attachment of a 60 drill stem thereto. Opposite side 4, 4, of the head, are tapered downwardly, and the lower end of the head has a deep transverse blade slot 5, between said tapered sides, extending entirely across said head, and whose upper 65 end is enlarged, forming a mortise, 6.

There is a key way 7, through the head, at substantially right angles to the axial plane of the slot 5, provided to receive the key 70 block 8. The head, beneath this keyway, is 75 configured to present the upper transverse end face 9, and the oppositely disposed, downwardly diverging, side faces 10, 10, with the spaced slots 11, 11, cut transversely through said faces.

There is a flat blade 12, of a general fish tail type, having oppositely disposed cutting edges, 13, 13. The blade is formed to be fitted edgewise into the slot 5 and its upper end has the spaced tenons 14, 14 which fit snugly 80 in the mortise 6 and form locking means between the blade and head. The lower end of the slot 5 is widened forming oppositely disposed, downwardly facing shoulders 15, 15, and the blade has the transverse, upwardly 85 facing shoulders 16, 16, extending entirely across each side thereof which abuts the corresponding shoulders 15, when the blade is in place in the head.

Between the tenons 14 the blade is cut away, 90 to provide the key space 17 which registers with the keyway 7, and the slots 18, 18 which register with the corresponding slots 11, 11, when the blade is in the head.

When the blade is inserted into place the 95 key block 8 is inserted through the keyway 7 and the underside of the key block has the transverse face 9' and the confronting, downwardly diverging faces 10', 10' which seat on the corresponding faces 9, and 10, 10 of the 100

head, and said block also is provided with the transverse ribs 19, 19 which key into the aligned slots 11, 18 of the head and bit, on each side. This block 8, with its under faces and ribs form secure locking means between the head and blade.

There is a tubular locking shaft 20 fitted down through an axial bearing 21 in the drill shank and whose upper end has a threaded connection with said shank. In the keyway 7 on the key block 8 a filler block 22 may be inserted, if desired. The locking shaft 20 extends through the filler block 22 and its lower end extends into the key block 8 and is reduced forming the external, annular, downwardly facing shoulder 23, provided to rest against the upper face of said key block 8.

An axial water course 24 leads from the channel 25, of the shaft 20 and continues on down through the key block 8 and through the blade, and at its lower end separates into the discharge ports 26, 26 which discharge the flushing fluid onto the cutting edges at, or near, the center of the bore.

The blade has also the side cutting, or reaming edges 27, 27 which extend out beyond the head, to ream out the bore as drilling progresses and behind each cutting edge 13 the head has the downward extensions, or braces, 28, 28 whose inner sides present flat faces, as 29, which fit closely against the blade and whose outer sides are convex as shown, for strength. The external surfaces of the key block 8 and filler block 22, conform to the contour of the head so as to give a smooth external contour to the complete drill.

When the parts are assembled the shaft 20 is screwed down so as to force the key block 8 securely in place and the blade will be thereby firmly locked in position. Should the blade become worn out or broken the shaft 20 may be unscrewed until its lower end clears the filler block 22 and said blocks 8 and 22 then removed and the blade taken out and a new one inserted. In this way a head can be used for an indefinite period of time at a great saving of expense and the drill can from time to time be renewed without any considerable loss of time.

If desired the blade may be additionally secured in place in the head by means of suitable bolts as 30 which extend through the head and into the blade as shown. The outer ends of these bolts are housed over by the key block 8 and if the blade should become split apart along a central vertical line, the parts will be held against dropping into the bore.

The drawings and description illustrate a preferred form of the device but it is to be understood that I do not wish to be limited to the exact form shown and described.

What I claim is:

1. A drill including a head having a blade slot extending transversely therethrough, a

blade fitted into said slot, a block in the head interlocked with the blade, an axial locking shaft having a threaded connection with the drill and whose inner end bears against said block.

2. A drill including a head having a blade slot therein, a blade in said slot, said head and blade each having a keyway therethrough and each also having a slot, said keyways and slots registering when the blade is assembled with the head, a key block fitted through said aligned keyways and having a rib which seats in said aligned slots.

3. A drill including a head having a blade slot therein, a blade in said slot, said head and blade each having a keyway therethrough and each also having a slot, said keyways and slots registering when the blade is assembled with the head, a key block fitted through said aligned keyways and having a rib which seats in said aligned slots, and releasable means through which said block, may be secured in interlocking relation with the head and blade.

4. A drill including a head having a blade slot therein, a blade fitted into said slot, an interlocking member in the head, said member, blade and head having intermeshing parts which interlock the blade and head, and an axial, locking, screw shaft incorporated into the drill and effective in one position to hold said member in such interlocking relation and in another position to permit the release of said member from such interlocking relation, said drill having a water course through said shaft, member, and blade which discharges at the lower end of the drill.

5. A drill including a head having a transverse slot formed with a mortise, a blade fitted into said slot and having a tenon which fits into said mortise, an interlocking member in the head, said head, blade and interlocking member being formed with intermeshing parts, and a shaft incorporated into the drill by threaded connections and effective when in one position to hold said member in such intermeshing position and when in another position to permit the release of said member from such intermeshing position.

6. A drill including a head having a transverse blade slot, a blade in said slot, a locking member through the head and whose inner end engages the blade, a key member through the head which fits over the outer end of said locking member and is provided with a rib, said blade having a slot in which said rib seats.

7. A drill including a head having a transverse blade slot, a blade in said slot, a locking member through the head and whose inner end engages the blade, a key member through the head which fits over the outer end of, and encloses, said locking member

and is provided with a rib, said blade having a slot in which said rib seats, and axial releasable means incorporated into the drill and abutting said key member and effective to lock the same in assembled relation with said head and blade.

8. A drill including a head having a transverse blade slot, a blade in said slot, a pair of screws fitted through the head from opposite sides and whose inner ends engage the blade, a key block extending transversely through the head and formed to interlock with the blade and to fit against the outer ends of said set screws, a releasable means 10 for locking said key block in place.

9. A drill having a head formed with a transverse blade slot, a blade in said slot, said head having a key way therethrough substantially at right angles to said slot said 20 head and blade having registering slots, said head having downwardly flared faces one on each side beneath said keyway, a key block fitted through said keyway and having downwardly flared faces which seat on said 25 faces of said head, said key block being provided with ribs which seat in said registering slots.

10. A drill having a head formed with a transverse blade slot, a blade in said slot, said head having a key way therethrough substantially at right angles to said slot said head and blade having registering slots, a key block fitted through said key way and provided with ribs which seat in said registering 35 slots, a filler block fitted through said key way adjacent the key block and releasable means having a threaded connection with the head and fitted through the filler block and abutting said key block.

11. A drill including a head having a transverse blade slot extending entirely therethrough and a key way through the head substantially at right angles to said slot, said keyway having flared ends forming 45 downwardly diverging faces on the head, a blade in said slot having a key space which substantially registers with the key way, when the blade is assembled with the head, a key block fitted through said keyway and 50 key space, said key block having diverging faces which fit against the respective head faces.

12. A drill including a head having a transverse blade slot and a key way substantially at right angles to said slot, the head beneath the key way having downwardly diverging faces, a blade in said slot having a key space which substantially registers with the key way, when the blade is assembled 55 with the head, a key block fitted through said key way and key space, said key block having diverging faces which fit against the respective head faces, means having a threaded connection with the head and abutting 60 said key block.

13. A drill including a head having a transverse blade slot and a key way substantially at right angles to said slot, the head beneath the key way having downwardly diverging faces, a blade in said slot having a 70 key space which substantially registers with the key way when the blade is assembled with the head, a key block fitted through said key way and key space, said key block having diverging faces which fit against the respective head faces, means having a threaded connection with the head and abutting said key block, said head and blade having registering slots and a rib carried by the key block and seated in said registering slots. 75

14. A drill including a head having a transverse blade slot and a key way substantially at right angles to said slot, the head beneath the key way having downwardly diverging faces, a blade in said slot having a key space which substantially registers with the key way, when the blade is assembled with the head, a key block fitted through said key way and key space, said key block having diverging faces which fit against the respective head faces, means having a threaded connection with the head and abutting said key block, said head and blade having registering slots and a rib carried 80 by the key block and seated in said registering slots. 85

15. A drill including a head, a detachable blade extending transversely therethrough, a member extending transversely through the head formed to interlock with the blade, an axial tubular shaft connected with the 100 head movable into one position to hold said member in said interlocking relation and into another position to permit the removal of said interlocking member.

In testimony whereof I have signed my name to this specification.
